UNITED STATES PATENT OFFICE.

EDWIN S. CARMAN, OF EAST CLEVELAND, OHIO, ASSIGNOR TO THE OSBORN MANUFACTURING COMPANY, OF CLEVELAND, OHIO, A CORPORATION OF OHIO.

MOLD-JARRING MECHANISM.

1,315,180.

Specification of Letters Patent. Patented Sept. 2, 1919.

Application filed November 30, 1915. Serial No. 64,257.

To all whom it may concern:

Be it known that I, EDWIN S. CARMAN, a citizen of the United States, and a resident of East Cleveland, county of Cuyahoga, and State of Ohio, have invented a new and useful Improvement in Mold-Jarring Mechanism, of which the following is a specification, the principle of the invention being herein explained and the best mode in which I have contemplated applying that principle, so as to distinguish it from other inventions.

The present improvements, relating as indicated to mold jarring mechanism, have special regard to the provision of means adapted for electrical actuation for jarring molds in mold-making machines; but it will be understood that some of the features involved are adapted for use in such machines, irrespective of the particular source of power. Such jarring mechanism, moreover, is herein shown as combined with a particular type of molding machine known as a roll-over jolt machine, and certain modifications and arrangements are peculiar to such combined use.

Where, as in the complete machine thus illustrated, electricity is used to actuate the jolt mechanism, it simplifies and unifies the construction to use the same source of power, that is electricity, for operating the roll-over mechanism, also.

The object of the present invention, accordingly, is to provide a roll-over jolt machine wherein electricity may be advantageously and economically used to operate the entire machine, both to preliminarily jolt, or jar, the table which supports the mold, and to subsequently roll such mold over. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Figure 1 is a plan view of a roll-over jolt mold-making machine, embodying my present improvements; Fig. 2 is a side elevational view of such machine showing the

foundations therefor in section; Fig. 2^a is a side elevational view of a portion of the actuating mechanism of the machine, viewed from the opposite side to that shown in Fig. 2; Fig. 3 is an end elevation of the same with not only the foundations but part of the machine itself appearing in transverse section; Fig. 3^a is a side elevational view, and Fig. 3^b a plan view, both on a larger scale of a portion of the jolting or jarring mechanism; Fig. 3^c is a section of a detail on the line C—C, Fig. 3^a; Fig. 4 is a diagrammatic view illustrating the mode of operation of the jolting or jarring mechanism; and Figs. 5 and 6 illustrate in plan and side elevation, respectively, a modified arrangement of the driving motors.

Save as modified to permit the use of electric power, the general constructional features of the present machine are similar to those of the mechanism for making molds, which forms the subject matter of my pending application, Serial No. 801,127, filed November 15, 1913. In other words, as indicated in Figs. 2 and 3, said machine is designed to be set in a pit 1, or at least below the floor line 2, on which the operators work, so that the roll-over table, or pattern plate carrier 3, in its lower position will be located only a short distance above the floor line, thus bringing a flask 4, when the same is secured thereon as shown in Fig. 3, in conveniently accessible position for filling with sand and for doing such tamping as may be found necessary. This roll-over table, which forms the central element of the machine, is, along with other various operative parts, supported on two end frames or standards 5, one at each end, that are in turn firmly secured to a bed plate 6 constituting the anvil of the jarring mechanism, as well. On the latter is also centrally mounted a tubular support in the form of a cylinder 7, in which is reciprocably fitted a tubular extension 8 that carries the jolting or jarring table 9. A housing 10, extending laterally from the side of said support, sustains and incloses the actuating mechanism for such table, as will be presently more fully described.

As in the machine which forms the subject matter of my co-pending application, in the normal position of the parts illustrated in Figs. 2 and 3, the roll-over table 3 rests on the jarring table or platform 9, 110

being designed, when in this position, to receive a mold-box or flask and to have the latter filled with sand, said platform and thus the table and flask, being jarred as occasion required by the aforesaid actuating mechanism so as to pack the sand around the pattern and pattern plate 60, which is directly secured to the face of the roll-over table.

10 For operative purposes, other than such jarring, this table is supported by means of trunnions 11 extending in opposite directions from side plates 12, that form part of the table structure, so as to lie in recesses 13 formed in the upper ends of two plungers 14 vertically reciprocable in guides 15 formed in the respective end standards. These recesses are in effect vertically extending slots of a length sufficient to permit the free up and down movement of the table, in the jarring operation just referred to, without the trunnions contacting with either end of the recesses. Upon the plungers, however, being raised the trunnions are engaged by the bottoms of the recesses, and the table thus lifted bodily to an elevation sufficient to permit of the rolling-over thereof in order to invert the pattern and attached flask, or mold box.

30 Actuation of the plungers thus to elevate the roll-over table, is secured from a rock shaft 20 extending transversely of the machine in front of the standards and provided with two arms 21, one at each end, 35 that are respectively connected by links 22 to the adjacent plungers.

The rolling-over of the table is designed to be automatically effected, incidentally to the raising of the latter by reason of the 40 rock shaft and its connections, two flexible members 25 being provided with this in view, one end of each of which is secured to an annular member in the form of a sheave 26 on one of the trunnions 11, and the other 45 end of which is attached to the adjacent standard 5, having a limited lost motion as the table is raised, so as not to interfere with the jarring operation, but eventually becoming fixed, whereby the table is rolled-over, if 50 raised sufficiently high.

55 A locking pin 27, normally operated inwardly by a compression spring 28, but adapted to be withdrawn by means of a hand wheel 29, is provided to retain the table in its rolled-over position, so that it may be lowered after thus being rolled-over and yet be retained inverted.

60 A self-equalizing flask carrier 30, mounted on a car or truck 31 is also provided, such 65 carrier being movable on rails 32 into and out of position under the table when thus inverted, and being adapted upon lowering of the inverted table to receive the mold box or flask 4, which is, of course, likewise inverted. Upon the flask being detached from

the table, the latter may be again raised sufficiently to clear the pattern and the carrier moved away with the finished mold. Thereupon the locking plunger 27 is released, and the table restored to its normal 70 position ready to receive another flask.

The jarring, or jolting mechanism, provided in connection with the jarring table, as clearly shown in Figs. 3, 3^a and 3^c, comprises a bell crank 35 pivotally hung to one 75 side of the tubular support 7, as at 36, and having its inner arm suitably pivotally connected to the tubular extension 8 of the jolting table, as by means of a slide-block 37 capable of reciprocable movement across the 80 face of the extension 8, the extension, as before stated, being reciprocably fitted in such support 7. The other arm of said bell-crank is connected by means of two links 38 of special construction (see Fig. 3^b) with 85 two cranks 39 that form part of a crank-shaft 40 disposed at substantially right angles to the shaft 20 for actuating the plungers 14, such cranks being disposed approximately 180 degrees apart. Each crank 90 it will be observed, has a lost motion connection with one of the links 38, being journaled in an elongated opening 41 formed between the one end of the link, and a block 42 slidably held therein. A compression 95 spring 43 interposed between said block and the other end of the link, serves to take up the shock or jar which might otherwise be imposed on the crank, solid buffers 44, 44 on the block and link end, which finally 100 contact, being adapted to receive the full load.

As a result of the foregoing construction it will be obvious that rotation of the crank-shaft 40 will serve to oscillate the bell-crank 35, so as to alternately raise the table support and allow it to drop, the angular location of the bell-crank relatively to the two cranks on the crank-shaft giving a long travel in the raising operation, and a short 110 travel for the drop; in other words, despite a slow upward movement, a rapid drop is secured under gravity and without its movement being restrained at all by the operating mechanism.

115 While the foregoing jolting or jarring mechanism is not necessarily limited to use with an electric drive, it is, by reason of the operative characteristics just pointed out, peculiarly adapted for use, and I accordingly preferably provide an electric motor 45, for rotating the crank-shaft 40, and at the same time utilize a second electric motor 46 to oscillate the rock-shaft 20 which raises and lowers the plungers 14. These 120 two motors, as illustrated in Figs. 1 and 2, are conveniently set together in a pit 47 adjacent that in which the molding machine is set, the shaft 40 being extended into such pit and there carrying a gear 48 of rela- 130

tively large diameter, wherewith meshes a pinion 49 on the armature shaft of the motor. A similar large gear 50 driven from the armature shaft of the other motor, carries a crank 51, having the necessary throw, which is in turn connected by means of a link 52 with a crank or lever-arm 53 on one end of said rock-shaft, as will be readily understood.

10 The foregoing arrangement and disposition of the motors permits of the control of the entire operation of the machine, both the preliminary jarring of the mold and the rolling-over of said mold, from any convenient station, and has the advantage that the rate of movement may be very nicely regulated, not only in the jarring operation, but in the rolling-over, to suit the size and character of the particular job being handled.

15 The particular construction of the jarring mechanism proper, and the advantages inherent therein, have already been set forth.

It might be further explained, however, 25 that the present arrangement is superior to the familiar cam, or toggle, frequently employed as the actuating means for a jarring table of the kind in hand, not only because the bearing surfaces of the moving parts 30 may be made of adequate size, but also because, by reason of the two cranks 39, angularly disposed as described, the table or support is picked up on the rebound. With such cam, or toggle, the load that can 35 be handled is limited on account of the relatively small bearing surface, especially in the case of the cam, and this explains the hitherto quite universal use of the so-called "air jolt" wherever a heavy load was involved.

40 By the present construction and arrangement of the two cranks in combination with the bell-crank, moreover, a long travel in raising the support is secured, and a short travel for dropping it; also the load 45 is picked up on the rebound, thus avoiding the harmful effect, when this is not done, such as disturbing the sand already packed about the mold.

In the modification illustrated in Figs. 5 50 and 6, I show a single motor 55 arranged to operate both the jolt-mechanism and the roll-over mechanism; in other words, such single motor is adapted to drive either gear 48 or gear 50, as desired. To this end, a 55 clutch 56 is provided on the shaft 57 of said motor, such clutch being adapted to connect said shaft either with a pinion 58 inter-gearred with said first-named gear, or a pinion 59 inter-gearred with the second 60 gear.

With this arrangement, the motor may be left running, and either mechanism operated as occasion demands by simply shifting said clutch one way or the other from its normal, 65 neutral position.

Other modes of applying the principle of my invention may be employed instead of the one explained, change being made as regards the mechanism herein disclosed, provided the means stated by any of the 70 following claims or the equivalent of such stated means be employed.

I therefore particularly point out and distinctly claim as my invention:—

1. In mechanism of the character described, the combination of a vertically reciprocal jarring platform; and means for actuating the same, including a bell-crank having one arm pivotally connected with said platform, a crank having its axis to 75 one side of the axis of said bell-crank, and a link connecting said crank and the other arm of said bell-crank.

2. In mechanism of the character described, the combination of a vertically reciprocal jarring platform; and means for actuating the same, including a bell-crank having one arm pivotally connected with said platform, a crank having its axis below 80 and to one side of the axis of said bell-crank, and a link having a lost-motion connection at one end with said crank and pivotally connected at its other end with the other arm of said bell-crank.

3. In mechanism of the character described, the combination of a tubular support; a jarring platform having an extension reciprocably fitted in said support; and means for actuating said platform, including a bell-crank oscillatory about an axis at 95 one side of said support and having one arm pivotally connected with said platform, a crank rotatable about an axis below and to one side of the axis of said bell-crank, a link having an elongated opening at one end 100 for connection with said crank and pivotally connected at its other end with the other arm of said bell-crank; and a resiliently-supported block in such opening adapted to take up the shock on said crank.

4. In mechanism of the character described, the combination of a vertically reciprocal jarring platform; and means for actuating the same including two independent cranks each having lost motion connection 105 with said platform.

5. In mechanism of the character described, the combination of a vertically reciprocal jarring platform; and means for actuating the same including two cranks rotating about the same axis and disposed approximately 180 degrees apart, said cranks 120 each having lost motion connection with said platform.

6. In mechanism of the character described, the combination of a vertically reciprocal jarring platform; and means for actuating the same including a pivotal supporting member operatively connected with 125 said platform and two cranks having inde- 130

pendent lost motion connection with said member.

7. In mechanism of the character described, the combination of a vertically reciprocable jarring platform; and means for actuating the same including an oscillatory crank member operatively connected with said platform and two rotatable crank members having independent lost motion connection with said oscillatory crank member.

8. In mechanism of the character described, the combination of a vertically reciprocable jarring platform; and means for actuating the same including an oscillatory crank member operatively connected with said platform and two crank members rotatable about the same axis and disposed approximately 180 degrees apart, said rotatable crank members having independent lost motion connection with said oscillatory crank member.

9. In mechanism of the character described, the combination of a vertically reciprocable jarring platform; and means for actuating the same including a bell-crank having one arm slidably and pivotally connected with said platform, two cranks rotatable about the same axis and disposed approximately 180 degrees apart, and two links each having a lost motion connection at one end with one of said rotatable cranks, and pivotally connected at its other end with the other arm of said bell-crank.

10. In mechanism of the character described, the combination of an anvil; a tubular support rising above said anvil; a jar-

ring platform having an extension reciprocably fitted in said support and adapted to contact with said anvil; and means for actuating said platform including a bell-crank oscillatory about an axis at one side of said support and having one arm slidably and pivotally connected with said platform, two cranks rotatable about an axis below and to one side of the axis of said bell-crank, said rotatable cranks being disposed approximately 180 degrees apart, and two links, each having a lost motion connection at one end with one of said rotatable cranks, and pivotally connected at its other end with the other arm of said bell-crank.

11. In mechanism of the character described, the combination of a jarring platform; a roll-over pattern-plate carrier normally resting on said platform; means adapted to roll said table over, upon its being raised; vertically reciprocable members adjacent to said platform, said members being normally out of engagement with said carrier but adapted to raise the same clear of said platform; and two electric motors, one of said motors being connected with said platform to jar the same, and the other thereof being connected with said members to alternately raise and lower the same.

Signed by me this 27th day of November, 1915.

EDWIN S. CARMAN.
